UNITED STATES PATENT OFFICE.

GEORGE H. TAYLOR, OF NEW YORK, N. Y.

DRESS-PROTECTOR TRIMMING.

SPECIFICATION forming part of Letters Patent No. 515,027, dated February 20, 1894.

Application filed September 6, 1893. Serial No. 484,907. (No model.)

To all whom it may concern:

Be it known that I, GEORGE H. TAYLOR, residing in the city, county, and State of New York, have invented an Improved Trimming for Apparel, of which the following is a specification.

This invention relates to a new construction of trimming which is particularly adapted for use as a dress protector, but which may also be used on other parts of ladies' and children's garments.

The invention consists in a trimming which is provided with a plain longitudinally extending tubular portion, having a stiffener therein, a doubled corrugated portion projecting therefrom, the corrugations of which extend at an angle to the longitudinally extending portion.

In the drawings, Figure 1 represents a face view of my improved trimming, showing it applied to a portion of ordinary fabric. Fig. 2 is an enlarged cross-section of the trimming, partly also in perspective; and Fig. 3 is a reverse view of that which is represented in Fig. 1.

In the drawings the letter A represents the trimming. This trimming is produced from a strip of fabric which is doubled or laid around a cord B, or analogous stiffener, forming a tube a around said cord. From this tube the strip of fabric is extended outward and is doubled preferably as shown at b, and this doubled portion placed against the edge or portion c of the strip that likewise protrudes from the tube a. In other words, starting with the edge c of the strip, it will be seen that said strip forms said edge c, next forms a tubular longitudinally extending portion a, and then forms the doubled elongated portion b which lies against the edge portion c. A line of stitching d may be employed to confine the parts in the described relation. That part of the strip of fabric which forms the doubled portion b is corrugated, fluted, or otherwise undulated, the corrugations extending at an angle to the longitudinally extending plain portion, while the remainder of said strip of fabric is not so undulated. The first effect of this corrugation is to round the

entire strip in manner indicated in Fig. 1, 50 since the corrugation produces a shortening in the part b without in corresponding manner shortening the part a. Hence the corrugation adapts the strip of fabric to the form needed as a dress-protector, allowing it, however, to be used also as a straight trimming whenever needed. The strip A thus formed may be stitched by a row of stitches e to the ordinary fabric D which is to carry the trimming, and if desired the outer end of the corrugated portion b may also be united to the fabric D by stitches f.

It is evident that my improved strip, instead of being made of a single piece of fabric, may if desired be composed of several 55 pieces, all when united forming substantially what is shown with reference to the strip constituting the parts c a and b.

The trimming is intended to be so applied to the fabric D that on one side the corrugated portion b and the tubular portion a will appear to view (as in Fig. 1), while on the other side (see Fig. 3) nothing but the tubular portion a will be visible.

What I claim, and desire to secure by Letters Patent, is—

1. The trimming, substantially as herein described, the same consisting of a plain, longitudinally extending, tubular portion, having a stiffener therein, a doubled corrugated 80 portion projecting therefrom, the corrugations of which extend at an angle to the longitudinal plain portion, substantially as and for the purposes specified.

2. The improved trimming herein described, 85 the same consisting of a folded strip of fabric having a plain, longitudinally extending tubular portion a, doubled corrugated projecting portion b, an edge c in contact with the corrugated portion, stiffener B contained 90 within said tubular portion, a line of stitches adjacent thereto for securing said stiffener therein, substantially as and for the purposes specified.

GEORGE H. TAYLOR.
